L. W. HOLLAND.

LATCH.

APPLICATION FILED JULY 24, 1917.

1,341,802.

Patented June 1, 1920.

UNITED STATES PATENT OFFICE.

LUTHER WATSON HOLLAND, OF PLEASANT HILL, MISSOURI.

LATCH.

1,341,802.

Specification of Letters Patent.

Patented June 1, 1920.

Application filed July 24, 1917. Serial No. 182,410.

To all whom it may concern:

Be it known that I, LUTHER WATSON HOLLAND, a citizen of the United States, and a resident of Pleasant Hill, in the county of 5 Cass and State of Missouri, have invented a new and useful Improvement in Latches, of which the following is a specification.

My invention relates to improvements in latches and it consists in the combinations, 10 constructions and arrangements herein described and claimed.

An object of my invention is to provide a simple form of lock, having a latch member which will spring in behind a latching 15 lug on the door, thereby latching the door and preventing its accidental opening.

A further object of my invention is to provide a spring-pressed latch member which is normally held out of operative position, 20 but which may be instantly brought into operative position by the pressure of the latching lug on a portion of the detent.

A further object of my invention is to provide a latch of extreme simplicity which 25 will obviate the necessity of slamming a door to latch it and yet which will retain the door in its latched position, thus obviating all danger of the door's coming open.

A further object of my invention is to 30 provide a latch of the type described having a handle whose movement releases the latch member, thus permitting the opening of the door when desired.

Other objects and advantages will appear 35 in the following specification and the novel features of the invention will be particularly pointed out in the appended claims.

My invention is illustrated in the accompanying drawings, forming part of this application, in which—

Figure 1 is a view from the inner side of the latch as applied to a door showing the latter in its open position,

Fig. 2 is a view similar to Fig. 1 showing 45 the door in its closed position with the parts in latching engagement,

Fig. 3 is an enlarged section along the line 3—3 of Fig. 1,

Fig. 4 is an enlarged section along the 50 line 4—4 of Fig. 2,

Fig. 5 is an enlarged section along the line 5—5 of Fig. 2,

Fig. 6 is an enlarged section along the line 6—6 of Fig. 2,

Fig. 7 is a perspective view showing the 55

main parts of the device ready to be assembled.

In carrying out my invention I provide a supporting frame which consists of a metal plate 1 having a flange 2 at one edge thereof. 60 This flange, as will be observed from Figs. 5 and 6, is not at right angles to the plate 1 but is at an obtuse angle. At 3 is a cut away portion which, as will be observed, includes a rectangular portion in the plate 1 and an 65 extension 3^x in the flange. On the inner side of the plate 1, that is to say, on the side on which the flange 2 is formed is a handle 4 made in the form of a bell-crank-lever which is pivoted at 5 to the plate 1. 70 In the drawing the handle is shown as being bent at right angles at the point 6, so as to present a flat side facing the front part of the latch. One end of the handle is formed into a latch plate having a beveled portion 75 4^y, this bevel being at an angle of eighteen degrees from the side of the handle parallel to the plate 1.

The end 4^y is arranged to swing past the opening 3 as shown in Fig. 7. A stop pin 80 4^x limits the movement of the handle 4 in one direction. At 7 in Fig. 7 I have shown a housing for a spring. This consists of a body portion having laterally extending flanges 7^a, ears 7^b being struck up from 85 these flanges. Tongues 7^c are arranged to enter openings 1^x in the plate 1, see Fig. 7, so as to secure the housing in position. As will be seen from the drawings, the flanges 7^a terminate short of the end of the housing 90 7 so as to leave a space 7^d into which the end of the handle 4 may project.

Referring again to Fig. 7, I have shown a detent which has a body portion 8. It is provided with a flange 8^a which is arranged 95 to fit over one end of the spring 7, and with trunnions 8^b arranged to enter the ears 7^b. The detent 8 has a flange 8^c which forms a stop or latch member for the handle 4, as will be hereinafter explained.

Arranged to coöperate with the lock is a strike plate having a body portion 9 and a flange 10 disposed at an obtuse angle thereto, with a latching lug 11 secured partly to the body portion and partly to 105 the flange. This latching lug is arranged to enter the openings 3 and 3^x in the plate 1 and the flange 2. The lug is provided with beveled portions 11^a and 11^b and it has a groove 11^c which faces the flange 10 so as to 110

form a slot into which the end 4^y of the handle 4 may enter. The face of this slot 11^c is beveled at eighteen degrees to conform with the bevel of the portion 4^y.

5 In assembling the parts the ears 7^e of the housing 7 are placed in the slots 1^x and are secured thereto by riveting or in any other suitable manner. The detent 8 is secured to the ears 7^b; a spiral spring 12 is disposed in 10 the housing with one end bearing on the portion 8^a of the detent and the handle is then secured in position so as to be pressed upon by one end of the spring 12.

From the foregoing description of the 15 various parts of the device, the operation thereof may be readily understood.

When the door is open the latch is in the position shown in Fig. 1 in which the handle 4 is swung toward the right, thereby compressing the spring 12 and permitting the flange 8^e of the detent to engage that portion 20 of the handle which constitutes a latch plate.

The strike plate is secured to the door frame 13 in the manner shown in Figs. 5 25 and 6. Now when the door is swung toward the strike plate the latching lug 11 will enter the opening in the lock and will engage the detent 8, pushing it away from the latch portion of the handle 4, so as to 30 permit the spring to enter the groove 11^c, thereby retaining the parts in position. The closed position is shown in Fig. 2 in which figure a portion of the detent 8 is broken 35 away to show the spring 12.

It will be observed that the beveling of the handle at 4^y and also of the latching lug at 11^c causes the door to be held firmly against the flange 10 of the strike plate. 40 The beveling of the latching lug at 11^b and 11^a tends to center the lug in the opening 3, thus counteracting any effect which may be produced by slight sagging of the door or lifting of the same.

45 The device has few parts, yet it positively latches the door and does not require slamming. A very slight pressure of the latching lug against the detent would be sufficient to cause the detent to disengage the 50 latch handle so that the latter will spring into position behind the lug.

Arrangement of the parts is such that the door is held in rigid position and a small spring is entirely sufficient to operate the 55 detent and the latch handle.

I claim:

1. The combination with a door jamb 60 having a lug, of a door having a latch, said latch having a casing provided with an opening arranged to receive the lug, a spring-pressed pivoted latch plate carried by said casing, a pivoted detent for holding the latch plate against the tension of the spring, said detent being arranged to be engaged by the lug, and to be moved to re-

lease the latch plate, thereby permitting the latter to enter between the lug and the casing of the latch.

2. The combination with a door jamb having a lug, of a door having a latch, said latch having a casing provided with an opening arranged to receive the lug, a spring-pressed pivoted latch plate carried by said casing, a movable detent arranged to engage the latch plate for holding the latter, said detent having a portion arranged to be engaged by the lug to release the latch plate, and a single spring, bearing at one end on said latch plate, and at the other end on said detent. 80

3. The combination with a door jamb having a lug, of a door having a latch, said latch having a casing provided with an opening arranged to receive the lug, a pivoted latch plate, a handle secured to said pivoted latch plate, a pivoted detent arranged to engage said latch plate for holding the latter in position, a spring disposed between the latch plate and the detent for placing the latch plate and the detent under tension, said detent being arranged to be engaged by the lug for releasing the latch plate to permit the entrance of the latter between the lug and the casing of the latch. 85

4. The combination with a door jamb having a latching lug, of a door provided with a latch, said latch having a casing provided with an opening arranged to receive the lug, a latch plate pivotally mounted on the casing of the latch and arranged to enter between the lug and the casing, a pivoted detent having a portion arranged to engage said latch for normally holding the latch plate out of engagement with said lug, a common spring for exerting tension on said latch plate and said detent, said detent having a projecting portion arranged to be engaged by said lug for releasing the latch plate. 95

5. In a latch, a casing having an opening, a latch plate having a portion adapted to be brought into registration with the opening, a movable detent having a portion arranged to engage said latch plate to normally hold the latter out of registration with the opening, a common spring for placing tension on the detent and on the latch plate, said detent also having a projection in registration with the opening, the movement of said projection serving to free the detent 110 from the latch plate and to permit the latter to spring into registration with said opening. 115

6. In a latch, the combination of a casing consisting of a flat plate having a flange at one side thereof, and an opening extending partly through the plate and partly through its flange, a bell-crank-lever pivotally mounted on the inner side of said plate and having an end arranged to be brought into registration with said opening, a detent 125 130

1. pivotally mounted on said plate and having a portion in registration with said opening, said detent also having a portion arranged to engage said bell-crank-lever for holding the latter out of registration with the opening, a spring for normally pressing said bell-crank-lever toward said opening and for pressing said detent toward said bell-crank-lever, the movement of the detent away from the plate serving to free the bell-crank-lever and to bring the latter under the tension of the spring into registration with the opening.

7. The combination with a door jamb, of a strike plate secured thereto and having a flange, a latching lug carried by said strike plate and having a groove facing the flange, a door having a latch, said latch having a casing provided with an opening arranged to receive the lug, a spring pressed latch plate carried by said casing, a movable detent for holding the latch plate against the tension of the spring, said detent being arranged to be engaged by the lug and to be removed to release the latch plate, thereby permitting the latter to enter between the lug and the flange on the strike plate.

8. The combination with a door jamb, of a strike plate having a latching lug secured thereto, a latch having a casing provided with an opening arranged to receive the latching lug, a pivoted latch plate carried by the casing, a spring for normally holding

said latch plate under tension, a housing for the spring, a pivoted detent carried by the housing for retaining the latch plate against the tension of the spring, said lug being arranged to enter the opening and to move the detent whereby the latch plate is released and is brought into latching engagement with said latching lug.

9. The combination with a fixed member having a lug, of a movable member having a latch, said latch having a casing provided with an opening arranged to receive the lug, a latch plate having a portion adapted to enter between the lug and the casing, a detent for normally holding the latch plate out of latching position and a single spring for placing both the latch plate and the detent under tension at all times.

10. The combination with a fixed member having a lug, of a movable member having a latch, said latch having a casing provided with an opening arranged to receive the lug, a latch plate having a portion adapted to enter between the lug and the casing, a detent for normally holding the latch plate out of latching position and a single spring bearing at one end on the latch plate and at the other end on the detent, and means for retracting the latch plate against the tension on the spring whereby the tension on the detent is increased.

L. W. HOLLAND.
